SVEN A. HALLBERG, OF CHICAGO, ILLINOIS.

STEAM SANDER AND CRYSTALLIZING-MACHINE.

1,162,603.

Specification of Letters Patent.

Patented Nov. 30, 1915.

Application filed April 7, 1913. Serial No. 759,521.

To all whom it may concern:

Be it known that I, SVEN A. HALLBERG, a citizen of the United States, residing at Chicago, in the county of Cook and State of Illinois, have invented certain new and useful Improvements in Steam Sanders and Crystallizing-Machines; and I do hereby declare the following to be a full, clear, and exact description of the invention, such as will enable others skilled in the art to which it appertains to make and use the same.

This invention relates to confectionery machines and as its principal object contemplates the provision of a machine for mechanically sanding and crystallizing gum drops.

It has heretofore been necessary in preparing gum drops or other similar confectionery for the market to perform by hand or by some few independent mechanical means the various steps and processes necessary in sanding and crystallizing the gum.

This invention therefore aims to provide a unitary plant for performing all the necessary steps in sanding and crystallizing the gum from the time it is received from the starching machine until it is a finished product, ready for the market.

A further object of this invention resides in the provision of means for progressively steaming, sanding and crystallizing the gum.

A yet further object is to construct the sanding device in such manner that all excess sugar applied to the gum in the sanding operation is automatically conveyed to an elevator by which it is carried again to the sanding chute for reapplication to the gum.

The above and additional objects are accomplished by such means as are illustrated in the accompanying drawings, described in the following specification and then more particularly pointed out in the claims which are appended hereto and form a part of this application.

With reference to the drawings, wherein I have illustrated the preferred embodiment of my invention as it is reduced to practice, and throughout the several views of which similar reference numerals designate corresponding parts: Figure 1 is a side elevation of the machine; Fig. 2 is a section on the line 2—2 of Fig. 1; Fig. 3 is a section on the line 3—3 of Fig. 1; and Fig. 4 is a sec-

tional view illustrating the means employed for adjusting the elevation of the steam jacket.

Proceeding now to the description of the drawings, this invention includes three main elements designed to successively steam, sand and crystallize the gum.

Steamer.—Taking up the three elements in the order named, the steamer of the machine includes a preferably cylindrical steam jacket 1 fixedly mounted in any suitable manner in a frame designated as an entirety in Fig. 1, by the numeral 2. The jacket 1 has a steam connection 1^a communicating therewith. The frame 2 consists essentially of a pair of longitudinal beams 3, and a pair of cross beams 4. The members 3 are pivotally mounted at their forward ends, as at 5, to the upper terminals of the vertical supporting leg 6 of a main supporting frame 7, as illustrated in Fig. 1. The frame 7 includes the vertical legs 6 and 7', the longitudinal beams 8 and 9, and cross beams 10 and 11. As a means for adjusting the inclination of the steam jacket 1, the frame 2 has been fixed only at the forward end, as above described, and is adjustably supported at its rear terminal through the medium of a threaded rod 12 attached by a bolt and socket joint at its upper terminal, as at 13, and operating through a suitable slot 14 formed in the cross beam 11 and beveled bed-rock 14 mounted thereon. The rod 12 operates in and is supported in the desired position by an internally screw threaded collar 15 carrying the laterally extending radial supporting arms 16, the free ends of which ride in arcuate slots 17 formed in the member 7', as is best illustrated in Fig. 4.

Rotatably mounted within the steam jacket 1 is a conveying drum 18, preferably formed of copper wires, although any other suitable foraminous metallic material may be used. The member 18 is fixed in any desirable manner on a shaft 19 journaled at each terminal in bearing standards 19 and 20, carried by the frame 2. The forward end of the shaft 19 is equipped with a bevel gear 21 disposed to mesh with a similar gear 22 keyed on a counter shaft 23, which latter member is journaled in bearing standards 24 and is driven by a belt connection

24' by a motor 25, or any other desired power source. On its lower side, and at the forward end thereof the jacket 1 is provided with an escape chute 26 arranged to conduct the steamed material from the drum 1 into the sanding mechanism to be next described.

5 Before proceeding to the description of the sanding mechanism, it is desirable to 10 explain briefly the operation of the steamer.

15 The gums are poured into a hopper 27 from which they pass into the drum 18 at the upper end thereof. As the drum rotates, the gums pass through the steam jacket 1, which is connected to any convenient steam supply, and during their passage through the steam jacket are thoroughly moistened, thus producing the adhesive surface necessary for the successful application of the sugar. It is, of course, apparent that the 20 extent to which the gums are moistened may be controlled both by regulation of the temperature in the steam jacket and by adjusting the frame 2 at various angles of inclination to effect a rapid or slow passage of the gums through the drum 18 in the manner above described.

30 *Sander.*—Following the steaming process, the gums are put through the so-called sanding process, which consists essentially in applying granulated sugar to the gums. As a means for mechanically sanding the gums, there has been provided a sanding chute 28 communicant at its upper terminal with the sand buckets 29 of the apron elevator 30, and communicant at its lower terminal with an angularly disposed chute 31. The elevator 30 may be inclosed in a casing 32, although this feature of the invention is an 35 unimportant one, inasmuch as any suitable type of elevator may be employed without departing from the spirit of this invention. As the gums pass through the chute 31, the sugar issues from the chute 28 covering the goods. The elevator is operated by a belt 40 connection to the motor 25. At its lower terminal the chute 31 communicates with a cylinder 32^a supported on a frame 33 and formed throughout the greater part of its 45 length of sheet metal, being constructed, however, at its forward end of copper screening or other suitable foraminous material 36 for a purpose to be hereinafter described. Within the cylinder 32^a is riveted, 50 or otherwise fixedly secured a progressive worm vane 34 carried on a shaft 35 which is journalized in the ends of the cylinder. It will thus be seen that actuation of the shaft 35 rotates the cylinder 32^a and worm 34 together. At its forward end and immediately 55 below the member 36 of the cylinder 32^a is arranged an escape funnel 37 adapted to conduct all excess sugar from the cylinder 32^a into the lower portion of the elevator 60 from whence it is again conducted by

the buckets 29 to the sanding chute 28. The shaft 35 is mounted in suitable bearings 38 carried by the frame 33 and is driven by a terminal bevel gear 39, which meshes with a similar gear 40 keyed to the shaft 41. The 70 shaft 41 is operatively connected through the drive pulley 42 by a belt 43. The member 42 may be connected to the driveshaft of the motor 25 in any desired manner.

Crystallizer.—As the gums reach the forward end of the cylinder 32, they pass through a chute 44 into a drying jacket 45, wherein they are subjected to a high degree of dry heat preferably produced by steam pipes 46 arranged within the jacket 45. 80 Since the steam jacket 1 requires a boiler it is of course more desirable and economical to heat the jacket 45 by steam pipes connected to the same boiler, but inasmuch as conditions concurrent with the adaption of this machine may vary, the jacket 45 has been designed to permit the utilization of gas or other dry heat producing fuel. It is of course apparent in this connection that if it is so desired a hot blast from a hot air furnace may be employed. The object of subjecting the gums, which have previously been moistened and sanded, to a high degree of dry heat in the jacket 45, is of course to absorb the moisture from the coating of 95 the gums, thus crystallizing the sugar. The jacket 45 is essentially a rectangular box equipped interiorly with the conveying apron 47 mounted on rollers 48, and actuated through a belt or chain drive 49 connecting the motor to a drive wheel keyed to the shaft of the rear roller 48. Upon reaching the forward end of the jacket 45, the gums pass through a discharge pipe 49 beneath which may be placed shelves or packing boxes 50. 100

105 The actual construction and operation of the machine being thus described, it now remains to enumerate the many advantages resulting from the novel structure employed in the preferred embodiment of this invention. 110 In this connection it is to be observed that this invention comprehends a unitary plant for sanding and crystallizing gum drops, operating to subject the gums to the three processes of steaming, sanding and crystallizing. Attention is also directed to the fact that the waste of sugar in the sanding process is avoided by providing means for reapplying the extra sugar to the gum drops. 115

120 In reduction to practice, I have found that the form of my invention, illustrated in the drawings and referred to in the above description, as the preferred embodiment, is the most efficient and practical; yet, realizing that the conditions concurrent with the adoption of my device will necessarily vary, I desire to emphasize the fact that various minor changes in details of construction, proportion and arrangement of parts may 125 130

be resorted to, when required, without sacrificing any of the advantages of my invention, as defined in the appended claims.

What is claimed is:

- 5 1. In a confectionery production sanding machine, a steamer for moistening the outer surface of the confection prior to the applying of sugar thereon, including a cylindrical steam jacket having communication with a steam supply source, a foraminous conveying drum rotatably mounted within said jacket, and means operatively connecting said drum to a prime mover for rotating said drum upon the operation of said prime mover.
- 10 2. In a confectionery product sanding machine, a steamer for moistening the outer surface of the confection prior to the applying of sugar thereon including a cylindrical steam jacket having communication with a steam supply source, a foraminous conveying drum rotatably mounted within said jacket, means operatively connecting said drum to a prime mover for rotating said drum upon the operation of said prime mover, said jacket and said drum normally resting on an incline, and means for vary-
- 15
- 20
- 25

ing the incline of said jacket and said drum for regulating the speed of travel of confection to said drum.

3. In a confectionery product sanding machine, a steamer for moistening the outer surface of the confection including a supporting structure having vertical standards, a steam jacket having communication with a steam supply source, a supporting frame for said jacket, said supporting frame having one end pivotally connected to said standard, a foraminous conveying drum rotatably carried within said jacket, means for rotating said drum for feeding confection therethrough, chutes communicating with the ends of said drum for feeding confection into and receiving it from said drum, and means carried by said supporting structure for varying the incline of said jacket and said drum for regulating the speed of passage of confection to said drum.

In testimony whereof I affix my signature in presence of two witnesses.

SVEN A. HALLBERG.
